LASTING MACHINE

Fred L. MacKenzie, Beverly, and Benjamin B. Blanchard, Swampscott, Mass., assignors to United Shoe Machinery Corporation, Paterson, N. J., a corporation of New Jersey

Application July 18, 1934, Serial No. 735,846

42 Claims. (Cl. 12—2)

This invention relates to lasting machines having means for shaping an upper over a last and means for fastening the upper in lasted relation to an insole or other shoe bottom part (hereinafter frequently referred to generically as the sole). It is an object of the invention, among others, to provide, in a machine for lasting shoes with driven fastenings, improved means for lasting a shoe or a portion thereof without driven fastenings, as when cement is used to secure the upper in lasted relation to the sole. The invention is illustrated as embodied in a machine of the type disclosed in Letters Patent No. 1,815,295, granted July 21, 1931, on an application of George Goddu, although it will be understood that in various novel aspects the invention is not limited to machines of that particular type. It is to be understood also that in some aspects the invention is not limited to machines having means for driving fastenings.

Machines of the type disclosed in the above-mentioned Letters Patent include in their organization means for pulling an upper over a last successively in different locations as the shoe is presented in different positions by the operator, and fastening-inserting mechanism comprising a staple-guiding nozzle movable inwardly over the bottom of the shoe to lay the marginal portion of the upper over the outer face of the sole, a driver for driving staples through said nozzle to fasten the upper to the sole, and a deflector for curving the legs of each staple prior to and during their entrance into the shoe to anchor them in the shoe. The present invention provides a novel organization including an overlaying device movable relatively to the fastening-inserting mechanism at the will of the operator into position to engage and wipe the marginal portion of the upper inwardly over the outer face of the sole while moving with the fastening-inserting mechanism over the bottom of the shoe in lasting with cement instead of driven fastenings, and means for operating the overlaying device by impact to force the overwiped margin of the upper into firm adherence to the sole. In the machine illustrated the fastening-inserting mechanism is moved inwardly over the bottom of the shoe as heretofore in a direction somewhat inclined toward the shoe bottom, after which it is moved, also as heretofore, toward the bottom face of the shoe in a direction substantially at right angles to the direction of its inward movement to insure that it will be close to the shoe bottom prior to the insertion of each fastening; and when the above-mentioned overlaying device is in use it receives corre-

sponding movements. The fastenings are inserted by a driver which is operated by mechanism arranged, in the construction herein shown, also to operate a hammer for delivering a blow to the above-mentioned overlaying device when the overlaying device is in position for use in lasting with cement. The present invention, in one important aspect, accordingly provides an overlaying device movable inwardly over the bottom of the shoe to lay or wipe the marginal portion of the upper over the outer face of the sole and then in a different direction toward the shoe to increase its pressure on the overwiped margin of the upper, after which its pressure is further increased substantially at the end of its second movement toward the shoe. The upper is, therefore, wiped tightly inward over the sole and is thereafter pressed with substantial firmness upon the outer face of the sole before the delivery of the blow by the hammer to insure firm adhesion of the cemented engaging faces of the upper and the sole.

Novel means is also provided for operating the driver for the fastenings in a retracted position so that it will not hit the staple deflector when the overlaying device is in use. As herein shown, the driver is operated by a lever which in turn is operated by a second spring-operated lever. The first lever is mounted on an eccentric which is connected to the overlaying device and is rotatable in response to movement of the overlaying device into or out of position for use to adjust the position of the first lever relatively to the second spring-operated lever to vary the extent of movement of the driver toward the deflector.

Machines of the type illustrated are provided with a shoe bottom rest, and a side gage arranged to engage the shoe substantially opposite the edge of the sole to determine the position of the shoe laterally and in cooperation with the bottom rest to determine the angular relation of its bottom face to the direction of forward movement of the fastening-inserting mechanism over the shoe. Preferably the shoe should be positioned with its bottom face in such angular relation to the direction of forward movement of the fastening-inserting mechanism as to provide a small amount of clearance between the fastening-inserting mechanism and the extreme edge of the shoe bottom as the fastening-inserting mechanism moves inwardly over the shoe. By providing the overlaying device, as herein illustrated, with a wiping portion between the staple nozzle and the shoe bottom, it will be seen that with the overlaying device in position for use an inward wipe may be applied to the upper substantially from

- the edge of the shoe bottom, as is desirable in lasting with cement, without varying substantially the angle at which the bottom face of the shoe is presented. In lasting with staples the position 5 of the shoe laterally is usually such that the staples are inserted substantially midway between the edge of the shoe bottom and the edge of the overlaid margin of the upper. In lasting with cement, however, the margin of the upper for 10 best results should be wiped inwardly over the shoe bottom for substantially its entire width. It will accordingly be seen that the position of the shoe laterally should be altered in lasting with cement to permit the overlaying device to move 15 farther inwardly over the sole for that purpose. Any rearward adjustment of the side gage widthwise of the shoe, however, necessitates a somewhat higher position of the gage, by reason of the angle at which the shoe is presented, if the 20 angle is to remain substantially the same. The machine is accordingly provided with novel means for adjusting the side gage, the construction shown comprising means for adjusting the gage both widthwise and heightwise of the shoe 25 into different positions for lasting with cement or with staples respectively, this adjustment of the gage being effected, as illustrated, by the same means that moves the overlaying device into and out of position for use.
- 30 The above and further features of the invention, including novel means for elevating the hammer in the return of the parts to starting positions and various novel details of construction and combinations of parts, will now be more particularly described by reference to the accompanying drawings and pointed out in the claims.
- 35 Fig. 1 is a view in side elevation looking from the left of the head of a machine in which the invention is embodied, showing the parts in the positions that they occupy in laying the marginal portion of the upper over the sole and fastening it with cement instead of with staples;
- 40 Fig. 2 is a view of a portion of the structure in side elevation, looking from the right, but showing the parts in the positions that they occupy in laying the marginal portion of the upper over the sole and fastening it with staples;
- 45 Fig. 3 is a view in side elevation looking from the right of a portion of the structure shown in Fig. 1;
- 50 Fig. 4 is a view partly in front elevation and partly in section of a portion of the head of the machine;
- 55 Fig. 5 is a view in front elevation of the overlaying device used in lasting with cement;
- Fig. 6 is a section on the line VI—VI of Fig. 3;
- Fig. 7 is a sectional view of the wire cutting, staple forming and transferring mechanism;
- 60 Fig. 8 is a plan view of a portion of the structure shown in Fig. 4, showing the relation of the parts when the above-mentioned overlaying device is in position for use;
- 65 Fig. 9 is a detail view of a portion of the mechanism shown in Fig. 8, but showing the parts in the positions they occupy when the overlaying device is in an idle position;
- Fig. 10 is a plan view of a portion of the mechanism shown in Fig. 8;
- Fig. 11 is a section on the line XI—XI of Fig. 70 10; and
- Fig. 12 is a perspective view of a shoe after it has been side lasted by the machine, showing the upper fastened to the sole by staples along the shank portion and by cement at the forepart.
- 75 The invention is illustrated as embodied in a

machine of the type disclosed in the above-mentioned Letters Patent and accordingly only such features of the general organization as it is necessary to refer to for an understanding of the invention will be described herein in detail.

5

It will be understood that the shoe on its last is supported in the hands of the operator and is presented successively in different positions in the progressive lasting of its opposite sides. To assist in determining the proper relation of the 10 shoe to the lasting instrumentalities the machine is provided with a side gage 10 arranged to engage the side of the shoe at or near the edge of the sole and with a shoe bottom rest 12 arranged to engage the outer face of the sole. The upper is 15 pulled over the last and the sole when the shoe is in each lasting position by a gripper comprising a pair of gripper jaws 14. For laying the marginal portion of the upper inwardly over the sole and fastening it with staples, there is provided a slide or carrier 16 (Fig. 1) which is movable along a guideway 18, formed on a member 19, in a forwardly and downwardly inclined direction toward the bottom of the shoe. For moving the slide 16 along its guideway toward and 20 from the shoe, there is formed in one side of a cam wheel 20 fast on a shaft 22 mounted in suitable bearings in the head of the machine, a path cam 24 (Fig. 1) which engages a roll 26 on the slide. This slide carries a staple guide or nozzle 30 25 and a staple driver 30, and a deflector 32 the lower end of which occupies a position opposite to the end of the staple-guiding passage in the nozzle 28 for engaging the legs of the staples and curving them prior to and during their entrance into the 35 shoe so that they are anchored in the sole without necessarily emerging from its inner face, as illustrated in Fig. 2. The operative movement of the driver is in a rearward direction and the deflector curves the legs of the staple forwardly 40 away from the edge of the sole. It will be understood that in the forward movement of the slide 16 prior to the driving of the staple the nozzle 28 and the deflector 32 act as overlaying means to lay the upper over the outer face of the sole. 45

The staple driver 30 is fastened to a driver slide 34 which is movable in a guideway formed in a bracket 36 secured to a forward extension of the slide 16. The driver slide 34 is operated by a lever 38 which is pivoted on a stud 40 on a forward 50 extension of the slide 16 and carries a lug 42 which extends into a recess in the driver slide 34. The lever 38 is operated by a bell-crank lever 44 which is pivoted on a rod 46 on the slide 16 and is operated in turn by a torsion spring 48 (Fig. 4). A 55 forwardly extending arm 45 of the bell-crank lever 44 carries a roll 50 (Fig. 1) which operates in a cam slot 52 in the lever 38, the cam slot being so formed that staple-driving movement is imparted to the lever 38 by upward movement of this arm. For swinging the bell-crank lever 44 against the resistance of the spring 48 to retract the driver 30 and to tension the spring, there is pivoted at 54 on the head of the machine a lever 56 on which is pivotally mounted at 58 a latch 60 arranged to 60 engage the lower end of a plate 62 fast on a downwardly extending arm of the bell-crank lever 44. A spring 64 connected to the latch 60 and to a pin on the lever 56 holds the latch in engagement with the plate 62 when the slide 16 and the parts carried thereby are in their initial positions. When the slide is moved forwardly toward the shoe, the latch 60 acts to swing the bell-crank lever 44, against the resistance of the spring 48, 65 in response to such forward movement, thereby 70 75

retracting the staple driver 30 as the latter is being carried bodily forward by the slide. For operating the latch 60 to release the lever 44 and thus to cause the operation of the driver, the 5 slide 16 carries a screw 66 the head of which is arranged to engage a shoulder on the latch, as illustrated in Fig. 1. The forward movement of the slide 16, however, does not carry the screw far enough to release the lever 44, such release 10 being effected in response to a swinging movement of the latch-carrying lever 56 after the slide 16 has completed its forward movement. For imparting to the latch-carrying lever its swinging movement there is provided in one side of the cam 15 wheel 20 (Fig. 1) a path cam 68 which engages a roll 69 carried by the lever 56. It will be understood that by reason of such movement of the lever 56 the screw 66 causes the latch 60 to swing far enough to disconnect it from the plate 62. 20 In the return of the parts to starting positions the latch 60 is held by a shoulder 70 on the lever 56 in position to connect again with the plate 62.

The machine is also provided with means for forming a staple in response to the forward movement of the slide 16 and for thereafter transferring the staple from forming position into alignment with the driver. For this purpose the slide 16 carries an inside former 72 (Fig. 7) arranged to cooperate with a stationary outside former 74. 25 Wire for forming the staples is fed automatically into position to be operated upon by the inside and outside formers through a nozzle 76 which is carried by the slide 16, this nozzle cooperating with a stationary shearing plate 78 to cut the wire. After the staple has been formed it is transferred downwardly into the path of movement of the driver by a transferring member 80 which operates between the inside and outside formers, this member being carried by a slide 82 30 (Fig. 1) movable in a guideway provided on the slide 16 and operated at the proper time by mechanism including a link 84.

The means for feeding the staple wire is substantially like that shown and described in Letters 45 Patent of the United States No. 1,796,451, granted March 17, 1931, on an application of George Goddu. The wire is mounted on a reel (not shown) and is operated upon by feed wheels 86, 88 (Fig. 4) from which it is conducted through a flexible tube 90 to the nozzle 76. The feed wheel 86 is operated by a pawl and ratchet mechanism through a link 92 and a bell-crank lever 94 provided with a roll 96 engaged by a cam 100. In order to stop the feed of the wire when desired 50 there is provided a lever 102 having thereon a projection 104 arranged to engage a face 106 on the lever 94 and thus to hold this lever in such a position as to prevent it from being operated by the cam 100.

The machine is further provided with means for imparting to the overlaying and fastening mechanism after it has been moved inwardly over the shoe bottom a movement in a different direction toward the bottom face of the sole to insure that it will be close to the shoe bottom immediately before the staple is driven. For this purpose the member 18 which provides a guideway for the slide 16 is secured by screws 108 (Fig. 1) to a holder 110 which has a downwardly extending portion fast on a rockshaft 112 mounted in the head of the machine. Secured also on the rockshaft 112 is a lever 114 carrying a roll 116 engaged by a path cam 118 formed in one side of a cam-wheel 120 on the cam shaft 22. It will 70 thus be seen that by the action of the cam 118 on the lever 114 the slide 16 and the fastening mechanism carried thereby are swung downwardly toward the bottom of the shoe in a direction substantially at right angles to the direction of their movement inwardly over the shoe. After driving the staple, the staple driver 30 remains at the end of its driving movement and the cam 118 is so shaped, as illustrated in Fig. 1, as to impart to the slide 16, immediately after the staple-driving operation and prior to the retractive movement of the slide along its inclined guideway, a reverse upward swinging movement which is of somewhat greater extend than the extent of its downward swinging movement prior to the driving of the staple. Thereafter, in time relation to the retractive movement of the slide 16 effected by the cam 24, the cam 118 swings the slide back to a normal position preparatory to operations on the next shoe.

In order that the machine herein shown may 20 be adapted to last a shoe, or a portion thereof, with cement instead of with staples, there is provided an overlaying device mounted upon the slide or carrier 16 and movable at the will of the operator into a position immediately below the 25 staple nozzle and deflector to act as a wiper to wipe the marginal portion of the upper inwardly over the sole. This overlaying device comprises a member 122 secured to a second member 123 (Figs. 2, 3 and 11) pivotally connected to a slide 30 124 mounted in a guideway formed in a bracket 126 fast on the slide 16. The member 122 extends forwardly (Figs. 2, 3 and 5) and has a relatively thin blade portion 125 at its forward end provided with a flat wiping face 127 which 35 is arranged to engage the upper over a greater extent lengthwise of the edge of the shoe bottom than the staple guide 28 and deflector 32. The member 123 carries an adjusting screw 129 which is held in engagement with a shoulder 131 on the 40 slide 124 by a compression spring 133 extending between the slide 124 and the member 123. It will be evident that by adjustment of the screw 129 the member 122 may be swung relatively to the slide 124 to vary the position of its wiping face height- 45 wise of the shoe, the screw 129 being preferably so adjusted that the overlaying member will be positioned with its wiping face substantially in parallel relation to the path of movement of the slide 16 along its guideway 18. The slide 124 is 50 controlled by a lever 128 pivotally connected to the bracket 126 and provided with an inwardly extending arm 130 (Figs. 5, 8 and 10) arranged to engage one or the other of a pair of pins 132, 134 carried by the slide 124 and extending upwardly through a slot 136 in the bracket 126, the construction being such that by swinging the lever 128 a forward movement may be imparted to the slide 124 to position the overlaying member 122 directly under the staple guide or nozzle 55 28 and the deflector 32 for wiping the upper inwardly over the sole while moving with the guide and deflector, as illustrated in Fig. 3, or a rearward movement may be imparted to the slide to move the overlaying member into a retracted 60 position to permit the lasting of the shoe with staples, as illustrated in Fig. 2. The length of the arm 130 is such that as the slide 124 completes either its forward or rearward movement a further swinging movement may be imparted to 70 the lever 128 to move the arm 130 relatively to the pin through which such movement was imparted to the slide into a position to lock the slide against movement in the opposite direction. By reference to Figs. 8 and 10, it will be seen that 75

when the overlaying member is in its forward position the pin 134 engages the bracket 126 at the forward end of the slot 136 and that the overlaying member is locked against rearward movement in response to pressure of the shoe against it by the engagement of the arm 130 with the pin 134. For imparting to the lever 128 its swinging movements, there is provided a hand lever 138 (Figs. 2, 3, 8 and 9) pivotally connected at 140 to a laterally extending arm 142 of a bracket 144 secured to the head of the machine. The hand lever 138 has a forwardly extending arm 146 to which there is connected by a ball and socket connection a rod 148 having adjustably fastened thereon a pair of collars 150 arranged to serve as abutments engaged by a stud 152 through which the rod 148 extends, the stud being pivotally connected to a downwardly extending arm 154 of the lever 128.

When the hand lever 138 is swung forwardly from the position shown in Fig. 8, the lever 128 is swung in a direction to move the arm 130 rearwardly. As the arm 130 moves rearwardly it engages the pin 132 and moves the overlaying member 122 rearwardly to an idle position, after which the arm 130 moves relatively to the pin 132 into a position to lock the slide 124 and the overlaying member against forward movement. To hold the hand lever 138 against movement relatively to the fixed arm 142 with the overlaying member either in a forward position for use as a wiper or in a retracted or inoperative position, there is provided a spring-pressed detent 156 carried by the lever 138 and arranged to engage one or the other of a pair of recesses 160 formed in the arm 142. When it is desired to move the overlaying member 122 forwardly into position to act as a wiper the hand lever 138 is swung rearwardly relatively to the arm 142 into the position shown in Fig. 8, and in order that the feeding of the wire will be interrupted so that no staple will be formed when the overlaying member is in position for use there is pivotally connected to a rearwardly extending arm 162 of the lever 138 a rod 164 extending through a recess in a stud 166 pivotally connected to the lever 102 and having fast thereon collars 168 arranged to engage the stud. When the hand lever 138, therefore, is swung rearwardly the lever 102 is swung to the left, to the position shown in Fig. 4, to interrupt the feeding of the staple wire.

In order to insure adequate adhesion of the overlaid margin of the upper and the sole when lasting the shoe with cement, the illustrated machine is provided with means for imparting to the overlaying device at the completion of its overlaying movement a hammer blow to cause the overlaying device to force the upper by impact against the bottom face of the sole. By reference to Figs. 2, 3 and 11 it will be seen that the member 123 to which the overlaying member 122 is secured has an upwardly extending arm 176. The upwardly extending arm 176 has a head 186 which, when the overlaying member is in its forward position, is beneath a hammer 188. The hammer is operated at a proper time in the cycle of the machine by a lever 190 which is pivoted on the stud 40 and has an upwardly extending arm 192 in which there is formed a cam slot 194 engaging a roll 196 carried by the forwardly extending arm 45 of the bell-crank lever 44 (Figs. 1, 2, 3 and 4). The cam slot 194 is so formed that, as the arm 45 moves upwardly the hammer 188 is swung in a direction to strike the arm 176 of the member 123. It will be

understood that the upward movement of the arm 45 takes place after the slide 16 has completed its forward movement along the inclined guideway 18 and substantially at the time when the swinging movements of the holder 110 and the slide 16 about the axis of the rockshaft 112 in a direction to move the overlaying member downwardly, have been completed. The overlaying member is thus moved inwardly over the shoe bottom to wipe the marginal portion of the upper inwardly over the sole, after which the overlaying member is moved in a different direction toward the shoe to increase its pressure on the overlaid margin of the upper before the blow is delivered to cause it to force the margin of the upper by impact against the sole to secure firm adhesion between the cemented engaging faces of the upper and the sole. The pressure of the overlaying device on the upper is then relieved by the upward swinging movement of the holder 110 and the slide 16 about the axis of the rockshaft 112 before the overlaying device is moved rearwardly from over the shoe, thus eliminating any possibility of such outward drag of the overlaying device on the margin of the upper as would tend to displace the upper from lasted position. The hammer 188 is adjustably secured to a laterally extending arm 198 of the lever 190 (Figs. 2 and 3). The hammer has a threaded upper portion 200 extending through a split bearing formed in the outer end of the arm 198 and a lower portion recessed to receive a fiber washer 204 which is arranged to engage the head 186 of the arm 176. It will be seen that by rotating the hammer in the bearing its position heightwise of the arm 198 may be varied so as to vary the force of the blow delivered to the overlaying member, a binding screw 206 being provided for drawing the two parts of the split bearing together to hold the hammer in adjusted position.

In order to prevent the driver 39 from striking the deflector 37 in the upward movement of the arm 45 when the overlaying member 122 is in position for use, there is provided means operative in response to forward movement of the slide 124 for shifting the position of the slide 34 in its guideway in the bracket 36 to vary the limit of movement of the driver toward the deflector. As shown particularly in Fig. 6, there is provided between the stud 40 and the levers 38 and 190 a sleeve 208 having a portion 210 upon which the lever 190 is mounted, which portion is concentric with the axis of the stud 40, and a portion 212 eccentric to the axis of the stud 40 and upon which the lever 38 is mounted. The sleeve is rotatably mounted on the stud and has a depending arm 216 (Figs. 2 and 3) at its outer end connected by a link 218 to the upwardly extending arm 176 of the member 123 which is carried by the slide 124. Thus as the slide 124 and the member 123 are moved forwardly by rearward movement of the hand lever 138, the sleeve 208 is rotated on the stud 40 and by reason of the eccentricity of the portion 212 of the sleeve, a swinging movement is imparted to the lever 38 about the axis of the roll 50 in a direction to impart to the slide 34, through the lug 42, a movement to the left (Figs. 2 and 3) to retract the driver. The driver is thus operated in a retracted position, when the overlaying device is in use, so that any danger of damaging the driver or the deflector, by interference between these parts, is avoided.

In the illustrated machine the position of the

shoe laterally is determined by the side gage 10 which is arranged to engage the shoe substantially opposite the edge of the sole, the position of the shoe heightwise in the machine being determined by the rest 12. Preferably the gage 10 and the rest 12 are so adjusted that, with the gage engaging the shoe in the location above described the shoe may be presented with its bottom face in such angular relation to the direction of forward movement of the stapling mechanism and in such heightwise relation to the stapling mechanism as to provide a small amount of clearance between the stapling mechanism and the extreme edge of the shoe bottom in the movement of the stapling mechanism over the shoe. Since the relatively thin blade portion 125 of the overlaying member 122 is directly beneath the stapling mechanism when the overlaying member is in position for use it will be evident that as the overlaying member moves inwardly over the shoe with the stapling mechanism it tends to engage the upper initially nearer the edge of the shoe bottom than the stapling mechanism and thus may wipe the margin of the upper inwardly substantially from the edge of the insole, as is desirable in lasting with cement. In lasting shoes with cement, however, the margin of the upper should preferably be wiped inwardly over the sole for substantially its entire width and, since the fastenings are inserted substantially midway between the edge of the shoe bottom and the edge of the overlaid margin of the upper in lasting the shoe with staples, the position of the shoe laterally should preferably be altered in lasting with cement in order to permit the overlaying member to move farther inwardly over the shoe bottom for that purpose. Any adjustment of the side gage rearwardly, however, to vary the position of the shoe laterally and thereby to vary the extent of inward movement of the overlaying member, necessitates a somewhat higher position of the gage by reason of the angle at which the bottom face of the shoe is presented, which should be substantially the same in lasting with cement as in lasting with staples. Accordingly, the illustrated machine is provided with means for adjusting the side gage 10 both widthwise and heightwise of the shoe to vary the position of the shoe laterally and to control the angular relation of its bottom face to the direction of forward movement of the stapling mechanism and the path of movement of the overlaying member over the shoe.

For the purpose in view the gage 10 is pivoted at 220 on a slide 222 which is adjustable horizontally along a guideway 224 (Figs. 1, 8 and 9) in the bracket 144 to vary the position of the gage 10 relatively to the rest 12 laterally of the shoe. The gage 10 has a rearwardly extending portion 226 (Fig. 1) in which there is formed a slot 228 and extending into the slot is a pin 230 projecting from the bracket 144. The slot 228 (Fig. 1) is disposed at an angle to the horizontal so that as the slide 222 is moved rearwardly in its guideway 224, the gage 10 is swung about its pivot 220 in a direction to move its shoe engaging end upwardly and as the slide 222 is moved forwardly the gage is swung in a direction to lower its shoe engaging end, the inclination of the slot 228 being such that as the slide 222 is adjusted in its guideway 224 the shoe engaging end of the gage 10 is moved away from or toward the rest 12 in a predetermined inclined path. The gage may accordingly be adjusted to vary the position of the shoe laterally without varying the angular relation of its shoe engaging end and the rest 12. The shoe may

thus be presented with its bottom face in substantially the same angular relation to the direction of movement of the different lasting instrumentalities of the machine in all adjusted positions of the gage to vary the position of the shoe laterally.

For adjusting the gage 10 to vary the position of the shoe laterally and to control the angular relation of the plane of its bottom face to the direction of movement of the lasting instrumentalities of the machine there are provided connections between the slide 222 and the mechanism hereinbefore described for moving the overlaying member into and out of position for use on the shoe. At its rear end the slide 222 is provided with a lengthwise slot 232 (Figs. 1, 8 and 9) to receive a block 234 which is held against movement relatively to the slide by a clamping screw 236. The block 234 has a transverse slot 238 (Fig. 1) and projecting into the slot is a pin 240 carried by one arm of a bell crank lever 242 pivoted at 244 to a rearwardly extending portion 246 of the bracket 144. The bell-crank lever 242 has a second arm 248 carrying a pin 250 which extends into a slot 252 formed in a link 254 pivoted to an arm 256 of the hand lever 138. The slide 222 is supported in its guideway 224 by a cover plate 258 (Fig. 1) secured to the bracket 144, and carried by the cover plate is a pin 260 (Fig. 3) which projects upwardly into a recess 262 formed in the under side of the slide 222. Mounted in the recess 262 between the pin 260 and a shoulder 264 formed on the slide 222 is a compression spring 266 which acts to move the slide 222 rearwardly and to hold it with a shoulder 268 on the slide in engagement with an adjustable stop, herein illustrated as a screw 270, carried by the cover plate 258. When the slide 222 and the gage 10 are in their rearward positions (Fig. 3) the overlaying member 122 is in position for use and the hand lever 138 is in the position indicated in Fig. 8. By reason of the pin and slot connection between the arm 248 of the bell-crank lever 242 and the link 254 it will be readily seen that by movement of the screw 270 the gage 10 may be adjusted toward or from the rest 12 to vary the position of the shoe laterally and thereby to vary the extent of inward movement of the overlaying member as may be necessary to take care of variations in the width of the lasting margins of the uppers of different shoes. It will be evident that with the parts in the positions shown in Fig. 3 rearward movement of the gage 10 is prevented by engagement of the shoulder 268 with the screw 270, the screw being held in adjusted position by means of a lock nut 272. By reference to Figs. 8 and 9 it will be seen that, as the hand lever 138 is swung forwardly from the position shown in Fig. 8 to the position shown in Fig. 9 to move the overlaying member 122 rearwardly to an idle position, the arm 256 of the lever 138 will be swung rearwardly thereby moving the link 254 from an inclined position into a substantially horizontal position. This movement of the link 254 acts through the pin 250 to impart to the bell-crank lever 242 a swinging movement in a direction to move the gage 10 against the resistance of the spring 266 forwardly into the position shown in Fig. 2, the construction being such that the gage is held against displacement rearwardly in response to pressure of the shoe against it by engagement of the pin 250 with the link 254 at the right-hand end of the slot 252.

In order that the position of the shoe laterally

may be varied in lasting with staples to vary the distance from the edge of the shoe bottom at which the staples are inserted, the illustrated machine is further provided with means for adjusting the side gage 10 toward or from the shoe rest 12 when the gage is in its forward position. As previously pointed out, the block 234 and the slide 222 are held against relative movement by a clamping screw 236. The screw 236, which is 10 threaded in the block 234, extends upwardly through a slot 274 in the slide 222, and has a collar 276 bearing against the bottom face of the slide. After loosening the screw 236 the slide 222 may be moved either forwardly or rearwardly in its guideway 224 to move the gage 10 toward or from the rest 12 after which the screw 236 may be tightened to hold the block and slide against relative movement with the gage in its adjusted position. It will be understood that 20 as the slide 222 is adjusted in its guideway to vary the forward position of the gage 10 the gage is also swung about its pivot 220 by reason of the engagement of the pin 230 with the gage in the slot 238 so that its shoe-engaging end moves 25 toward or from the shoe rest 12 in a predetermined inclined path thus maintaining it at all times in the same angular relation to the shoe rest 12.

When the machine is initially at rest the slide 30 16 is in its retracted position, and in order that the hand lever 138 may be swung, by the operator, at that time either forwardly to set the machine to last the shoe with staples, or rearwardly to move the overlaying member 122 into position for use in lasting the shoe with cement, without interference between the hammer 188 and the arm 176 of the member 123, the illustrated machine is provided with means for imparting to the lever 44 a movement in a direction to raise the hammer 188 enough to clear 35 the arm 176 in the return of the parts to starting positions. As shown particularly in Figs. 1 and 3, the lever 44 has an upwardly extending arm 278 which is arranged near the end of the retractive movement of the slide 16 along its guideway 18 to engage a roll 280 mounted on an eccentric stud 282 secured to the head of the machine. Thereafter as the slide 16 continues its retractive movement toward starting position the 40 bell-crank lever 44 is swung, in response to the action of the roll 280 on the arm 278, in a direction to lower the arm 45 and to move the plate 62 toward the latch 60, the arrangement of the parts being such that as the slide 16 completes its retractive movement sufficient 45 swinging movement is imparted to the lever 44 to move the plate 62 into position to connect with the latch 60 which is made somewhat shorter than heretofore in machines of the illustrated type. The downward movement of the arm 45 acts to swing the lever 190 in a direction to raise the hammer 188. It will thus be seen that there will be no frictional drag of the hammer on the head 186 of the arm 176 as the hand 50 lever 138 is swung about its pivot by the operator either rearwardly to move the arm 176 beneath the hammer 188 or forwardly to move the arm 176 from beneath the hammer 188. It will be understood that for convenience the roll 55 280 is mounted on the eccentric stud 282 which may be adjusted to vary the position of the roll and thus to vary the time in the retractive movement of the slide 16 when the arm 278 engages the roll. Thus the amount of swinging 60 movement imparted to the lever 44 may be varied.

ried to insure that the plate 62 will be swung far enough to connect with the latch 60 by the time when the slide 16 completes its retractive movement.

Having described the invention, what we claim 5 as new and desire to secure by Letters Patent of the United States is:

1. In a lasting machine, the combination with means for shaping an upper over a last, and means for fastening the upper to a sole on the last comprising fastening-inserting mechanism movable inwardly over the bottom of the shoe for laying the marginal portion of the upper over the outer face of the sole and fastening the upper to the sole by driven fastenings, of an 15 overlaying device movable relatively to said fastening-inserting mechanism into position to apply to the marginal portion of the upper an inward wipe while moving with the fastening-inserting mechanism over the shoe bottom in lasting the shoe with cement instead of with driven fastenings, and means for operating said overlaying device by impact to cause it to force the overlaid margin of the upper more firmly into adhering relation to the sole. 25

2. In a lasting machine, the combination with means for shaping an upper over a last, and means for fastening the upper to a sole on the last comprising fastening-inserting mechanism movable inwardly over the bottom of the shoe 30 for laying the marginal portion of the upper over the outer face of the sole and for fastening the upper to the sole by fastenings inserted through the upper and into the sole, of a device movable relatively to said fastening-inserting mechanism into position for use to lay the marginal portion of the upper inwardly over the sole while moving with said fastening-inserting mechanism over the shoe bottom in lasting the shoe with cement instead of with driven fastenings, and means for imparting to said device at the completion of its inward movement a hammer blow to cause it to force the upper by impact against the outer face of the sole. 35

3. In a lasting machine, the combination with 40 means for shaping an upper over a last, and means for fastening the upper to a sole on the last comprising fastening-inserting mechanism movable inwardly over the bottom of the shoe into upper-fastening position and having means for 45 curving each fastening prior to and during its entrance into the shoe to anchor it in the shoe, of a device movable relatively to said fastening-inserting mechanism into position for use to wipe the margin of the upper inwardly over the sole 50 while moving with said fastening-inserting mechanism over the shoe bottom in lasting the shoe with cement instead of with driven fastenings, and a member for imparting to said device at the completion of its inward movement a hammer 55 blow to increase the pressure of said device on the overlaid margin of the upper. 60

4. In a lasting machine, the combination with means for shaping an upper over a last, and fastening-inserting mechanism movable inwardly 65 over the bottom of the shoe to lay the marginal portion of the upper over a sole on the last and to fasten the upper to the sole by driven fastenings, of an overlaying device mounted for movement at the will of the operator into position for use to 70 engage and wipe the marginal portion of the upper inwardly over the sole in lasting the shoe with cement instead of with driven fastenings, means for rendering the fastening-inserting means ineffective to insert fastenings when said 75

device is in position for use, and mechanism into operative relation to which said device is carried in its movement into position for use for imparting to the device a hammer blow to increase the pressure of the device on the overlaid margin of the upper.

5. In a lasting machine, the combination with means for shaping an upper over a last, and means for fastening the upper to a sole on the last comprising a guide for fastenings movable inwardly over the bottom of the shoe to lay the marginal portion of the upper over the sole, a driver for driving the fastenings, and means for operating the driver, of a device mounted for 10 movement into position for use to wipe the upper inwardly over the sole while moving with said fastening means over the shoe bottom in lasting the shoe with cement instead of with driven fastenings, and means arranged to be operated by 15 said driver-operating means for delivering a blow to said device at the end of its inward movement to cause it to force the upper into firm adherence to the sole.

6. In a lasting machine, the combination with means for shaping an upper over a last, and means for fastening the upper to a sole on the last comprising a guide for fastenings movable inwardly over the bottom of the shoe to lay the marginal portion of the upper over the sole, and a driver for driving the fastenings, of a device movable relatively to said guide at the will of the operator into position for use to lay the marginal portion of the upper inwardly over the sole and press it upon the sole while moving with said 30 guide inwardly over the shoe bottom in lasting the shoe without driven fastenings, and means operative in response to movement of said device into position for use to vary the initial position 35 of the driver and thus to vary the limit of its movement toward the work.

7. In a lasting machine, the combination with means for shaping an upper over a last, and means for fastening the upper to a sole on the last comprising a guide for fastenings movable inwardly over the bottom of the shoe to lay the marginal portion of the upper over the sole, and a driver for driving the fastenings, of a device movable relatively to said guide at the will of the operator into position for use to wipe the marginal portion of the upper inwardly over the sole and press it upon the sole while moving with said 40 guide inwardly over the shoe bottom in lasting the shoe without driven fastenings, and means for operating the driver in a retracted position when said device is in use.

8. In a lasting machine, the combination with means for shaping an upper over a last, and means for fastening the upper to a sole on the last comprising a guide for fastenings movable inwardly over the bottom of the shoe to lay the marginal portion of the upper over the sole, a driver for driving the fastenings, and means for operating the driver, of a device movable relatively to said guide at the will of the operator into a position to engage and wipe the upper inwardly over the sole while moving with said guide over the shoe bottom in lasting the shoe without driven fastenings, a member for controlling said device, and means for moving said driver relatively to its operating means into a retracted position when said device is moved into position for use by said member.

9. In a lasting machine, the combination with means for shaping an upper over a last, and

means for fastening the upper with staples to a sole on the last comprising a driver for driving staples and a deflector for curving the legs of each staple prior to and during their entrance into the shoe to anchor them in the shoe, of a device arranged for use to wipe the marginal portion of the upper inwardly over the outer face of the sole and to press it into position to adhere to said face in lasting the shoe with cement instead of with staples, and a member 10 movable by the operator to control said device and also to retract the driver to vary the limit of its movement toward the deflector when said device is in use.

10. A lasting machine having, in combination, means for shaping an upper over a last, a guide for fastenings, a carrier for moving said guide inwardly over the bottom of a shoe into upper-fastening position prior to the driving of each fastening, an overlaying device supported by said 20 carrier and movable relatively thereto into and out of such relation to the guide as to wipe the upper over the outer face of the sole while moving with said guide inwardly over the shoe bottom, a driver for driving the fastenings, a hammer for striking said overlaying device, a single means for operating the driver and the hammer, and means controlled by the movement of the overlaying device into and out of such relation to the guide for varying the position of the driver 30 relatively to its operating means to vary the limit of its movement toward the work.

11. In a lasting machine, the combination with means for shaping an upper over a last, and fastening-inserting mechanism movable inwardly over the bottom of the shoe in a direction inclined toward its bottom face into upper-fastening position prior to the driving of a fastening, of a device movable relatively to said fastening-inserting mechanism at the will of the operator 40 into position for use to wipe the upper over a sole on the last while moving with said fastening-inserting mechanism over the bottom of the shoe in lasting the shoe with cement instead of with driven fastenings, a member for controlling said 45 device, a hammer, and means for operating said hammer to deliver a blow to said device at the end of its overwiping movement and for elevating said hammer after the blow has been delivered to permit free movement of said device into 50 and out of position for use.

12. A lasting machine having, in combination, means for shaping an upper over a last, fastening-inserting mechanism, a carrier for said fastening-inserting mechanism movable forwardly 55 to carry the fastening-inserting mechanism inwardly over the shoe bottom into upper-fastening position prior to the driving of a fastening and thereafter movable rearwardly to retract the fastening-inserting mechanism, an overlaying 60 device movable relatively to said fastening-inserting mechanism at the will of the operator into position for use to wipe the marginal portion of the upper over the outer face of a sole on the last while moving with said fastening-inserting 65 mechanism inwardly over the bottom of the shoe in lasting the shoe with cement instead of with driven fastenings, a hammer, means for operating said hammer to deliver a blow to said overlaying device after the carrier has completed its 70 forward movement, and means arranged to impart to said last-named means movement in a direction to retract the hammer in response to rearward movement of the carrier.

13. In a lasting machine, the combination with 75

- means for shaping an upper over a last, and means for fastening the upper to a sole on the last comprising fastening-inserting mechanism, and a carrier movable forwardly to carry said 5 fastening-inserting mechanism inwardly over the bottom of the shoe into upper-fastening position and movable thereafter rearwardly to retract the fastening-inserting mechanism, of an overlaying device supported by said carrier, a slide mounted 10 on said carrier for moving said overlaying device into and out of such relation to said fastening-inserting mechanism as to lay the marginal portion of the upper over the sole while moving with said fastening-inserting mechanism over 15 the shoe bottom in lasting the shoe with cement instead of with driven fastenings, a controlling member for moving the slide, a spring-operated hammer on said carrier for striking said overlaying device at the completion of its inward movement to increase the pressure of said device on 20 the upper, and means operative in response to rearward movement of the carrier to raise the hammer and thus to prevent frictional drag of the hammer on the overlaying device in the movement of the slide by the controlling member.
14. In a lasting machine, the combination with 25 means for shaping an upper over a last, and means for fastening the upper to a sole on the last comprising a guide for fastenings and a carrier movable forwardly to carry said guide inwardly over the bottom of the shoe into upper-fastening 30 position and movable thereafter rearwardly to retract the guide, of an overlaying device movable relatively to said guide at the will of the operator into position to wipe the marginal portion 35 of the upper over the sole while moving with the guide inwardly over the shoe bottom in lasting the shoe with cement instead of with driven fastenings, a hammer for delivering a blow to said overlaying device, a spring-operated lever for 40 operating the hammer, a latch for swinging said lever in a direction to raise the hammer and to tension its operating spring by the forward movement of the carrier, means for operating the 45 latch to release the spring-operated lever for the operation of the hammer after the completion of the inward movement of the overlaying device, and means for moving the hammer out of engagement with the overlaying device in response 50 to rearward movement of the carrier comprising a stop arranged by engagement with said spring-operated lever to impart to it a reverse swinging movement into latching position.
15. In a lasting machine, the combination with 55 means for shaping an upper over a last, and fastening-inserting mechanism movable inwardly over the bottom of the last in a direction inclined toward its bottom face into upper-fastening position prior to the driving of a fastening, of an overlaying device movable relatively to said fastening-inserting mechanism at the will of the operator into position to engage and wipe the marginal portion of the upper over the outer face 60 of a sole on the last while moving with said fastening-inserting mechanism inwardly over the bottom of the shoe in lasting the shoe with cement instead of with driven fastenings, a carrier for moving said fastening-inserting mechanism inwardly over the bottom of the shoe and relatively to which said overlaying device is movable into and out of position for use, a hammer for 65 delivering a blow to said overlaying device, and automatic means for imparting to said carrier substantially at the end of the inward movement 70 of the overlaying device a downward movement

toward the bottom face of the shoe to increase the pressure of said device on the overwiped margin of the upper before the delivery of the blow by said hammer.

16. In a machine for lasting shoes in which the marginal portion of the upper is secured in lasted relation to a sole by an adhesive, a member movable inwardly over the bottom of the last for laying the marginal portion of the upper over the outer face of a sole on the last, means for imparting to said member at the completion of its inward movement a movement in a direction heightwise of the shoe toward the bottom face of the sole to increase the pressure of said member on the overlaid margin of the upper, and additional means for further increasing the pressure of said member on the upper substantially at the end of its second movement.

17. In a machine for lasting shoes in which the marginal portion of the upper is secured in lasted relation to a sole by an adhesive, an overlaying device movable inwardly over a shoe in a direction inclined toward its bottom face to lay the marginal portion of the upper over a sole and then in a different direction to press the overlaid margin 25 of the upper throughout substantially its entire width against the sole, and means for operating said device by impact substantially at the end of its second movement to cause it to force the overlaid margin of the upper more firmly into ad- 30 hering relation to the sole.

18. In a machine for lasting shoes in which the marginal portion of the upper is secured in lasted relation to a sole by an adhesive, the combination with means for shaping an upper over a last, of a device movable inwardly over the bottom of the shoe for wiping the marginal portion of the upper over a sole on the last, means for imparting to said device substantially at the end of its inward movement a movement in a different direction to 40 increase its pressure on the overlaid margin of the upper, and means constructed to act on said device by impact further to increase its pressure on the upper.

19. In a machine for lasting shoes in which the marginal portion of the upper is secured in lasted relation to a sole by an adhesive, the combination with means for shaping an upper over a last, of an overlaying device, means for imparting to said overlaying device a movement inwardly over the 50 shoe in a direction inclined toward the bottom of the last to cause said device to lay the marginal portion of the upper over a sole on the last and then a movement in a direction substantially at right angles to the direction of its inward movement to increase its pressure on the overlaid margin of the upper, and means operative in time relation to said last-named means for imparting to said device a hammer-blow to cause it to force the upper by impact more firmly into adhering 60 relation to the sole.

20. In a machine for lasting shoes in which the marginal portion of the upper is secured in lasted relation to a sole by an adhesive, the combination with means for shaping an upper over a last, of an overlaying device movable inwardly over the shoe in a direction inclined toward its bottom face for wiping the marginal portion of the upper over a sole on the last and then in a direction substantially at right angles to the direction of its inward movement to press the overwiped margin of the upper upon the sole, and a member for delivering a blow to said overlaying device substantially at the end of its second movement toward the shoe 75

to cause firm adherence between the cemented engaging faces of the upper and the sole.

21. In a machine for lasting shoes in which the marginal portion of the upper is secured in lasted relation to a sole by an adhesive, an overlaying device movable inwardly over the bottom of the last for laying the marginal portion of the upper over a sole on the last and pressing it into position to adhere thereto, a hammer, means for operating the hammer to deliver a blow to said overlaying device to cause it to force the margin of the upper into firm adherence to the sole, and means for imparting to said overlaying device movement in a different direction from that of its inward movement over the shoe to increase the pressure of said device on the overlaid margin of the upper prior to the operation of said hammer.

22. In a machine for lasting shoes in which the marginal portion of the upper is secured in lasted relation to a sole by an adhesive, an overlaying device movable inwardly over the bottom of the last for laying the marginal portion of the upper over a sole on the last, a hammer, means for operating said hammer to deliver a blow to said overlaying device to force the overlaid margin of the upper into adhering relation to the sole, and mechanism automatically operative independently of said hammer-operating means to impart to said device movement in a different direction from that of its inward movement to increase the pressure of said device on the overlaid margin of the upper in time relation to the operation of the hammer.

23. In a machine for lasting shoes in which the marginal portion of the upper is secured in lasted relation to a sole by an adhesive, an overlaying device movable inwardly over the bottom of the last for laying the marginal portion of the upper over a sole on the last, means for imparting to said overlaying device its inward movement, a hammer for imparting a blow to said overlaying device, and additional means for effecting relative movement of said overlaying device and the shoe to increase the pressure of the overlaying device on the upper before the delivery of the blow by said hammer.

24. In a machine for lasting shoes in which the marginal portion of the upper is secured in lasted relation to a sole by an adhesive, an overlaying device mounted for rectilinear movement inwardly over the bottom of the last for laying the marginal portion of the upper over a sole on the last, a spring-operated hammer for delivering a blow to said overlaying device, and additional means automatically operative substantially at the end of the inward movement of said overlaying device to impart to it a swinging movement toward the bottom of the shoe in time relation to the operation of the hammer.

25. In a machine for lasting shoes in which the marginal portion of the upper is secured in lasted relation to a sole by an adhesive, the combination with means for shaping an upper over a last, of an overlaying device movable inwardly over the bottom of the last to lay the marginal portion of the upper over the outer face of a sole on the last and to press it into position to adhere to said outer face, and means for operating said device by impact to force the overlaid margin of the upper more firmly into adhering relation to the sole comprising a hammer, a lever for operating said hammer, a second spring-operated lever for imparting operative movement to said first lever, and means operative in response to inward movement of said overlaying device to

retract the spring-operated lever against the resistance of its spring.

26. In a lasting machine, the combination with means for shaping an upper over a last, of a device for wiping the marginal portion of the upper inwardly over a sole on the last and for pressing it into position to adhere to the sole through the action of cement, a carrier for moving said device inwardly over the sole in wiping engagement with the upper, and means for imparting to said device a hammer blow to cause it to force the overlaid margin of the upper into firm adherence to the sole comprising a spring-operated hammer, a member for retracting said hammer and for tensioning its operating spring by the movement of the carrier, and means for operating said member to release the hammer to the action of its operating spring after said device has completed its inward movement.

27. In a lasting machine, the combination with means for shaping an upper over a last, of a device for wiping the marginal portion of the upper inwardly over a sole on the last and for pressing it into position to adhere to the sole through the action of cement, a carrier for moving said device inwardly over the sole in wiping engagement with the upper, a hammer for delivering a blow to said device to cause it to force the overlaid margin of the upper by impact against the sole, a spring-operated lever for operating the hammer, a latch for retracting said spring-operated lever against the action of its spring by the movement of the carrier, and means operative in time relation to the movement of the carrier for moving said latch to release the spring-operated lever for the operation of the hammer.

28. In a machine for lasting shoes in which the marginal portion of the upper is secured in lasted relation to a sole by an adhesive, a device for wiping the marginal portion of the upper inwardly over the outer face of a sole on the last, a support for moving said device inwardly over the bottom of the shoe in wiping engagement with the upper, said device being mounted on its support for swinging movement heightwise of the shoe, a hammer on said support for striking said device at the completion of its inward movement to increase the pressure of said device on the upper, and a spring tending to swing said device upwardly while permitting it to yield downwardly in response to the action of the hammer thereon.

29. In a lasting machine, the combination with means for pulling an upper over a last successively in different locations along the side of the last as the shoe is presented by the operator in different positions, a shoe bottom rest and a side gage for controlling the shoe, and upper-fastening mechanism constructed to drive fastenings and movable inwardly over the bottom of the shoe into upper-fastening position prior to the driving of each fastening through the upper and into the sole, of a device movable relatively to said upper-fastening mechanism at the will of the operator into position for use to lay the marginal portion of the upper inwardly over the sole while moving with said upper-fastening mechanism over the bottom of the shoe in lasting the shoe with cement instead of with driven fastenings, and means for adjusting the position of the side gage both widthwise and heightwise of the shoe as said device is moved into position for use.

30. In a lasting machine, the combination with means for pulling an upper over a last successively in different locations along the side of the

- last as the shoe is presented by the operator in different positions, a shoe bottom rest and a side gage for controlling the shoe, and upper-fastening mechanism constructed to drive fastenings and movable inwardly over the bottom of the shoe into upper-fastening position prior to the driving of each fastening through the upper and into the sole, of a device movable relatively to said upper-fastening mechanism at the will of the operator into position for use to wipe the marginal portion of the upper inwardly over the sole while moving with said upper-fastening mechanism over the bottom of the shoe in lasting the shoe with cement instead of with driven fastenings, means for adjusting the position of the side gage widthwise of the shoe as said device is moved into position for use, and means for varying the position of the side gage heightwise of the shoe in response to its movement widthwise of the shoe.
31. In a lasting machine, the combination with means for pulling an upper over a last successively in different locations along the side of the last as the shoe is presented by the operator in different positions, a shoe bottom rest and a side gage for controlling the shoe, and upper-fastening mechanism constructed to drive fastenings and movable inwardly over the bottom of the shoe to lay the marginal portion of the upper over a sole on the last prior to the driving of the fastening through the upper and into the sole, of an overlaying device mounted for movement into position for use to lay the marginal portion of the upper inwardly over the sole while moving with said upper-fastening mechanism in lasting the shoe with cement instead of with driven fastenings, a member for moving said device into and out of position for use on the shoe, and means controlled by said last-named member for moving the side gage into different positions widthwise of the shoe to vary the position of the shoe laterally in lasting the shoe with cement or with driven fastenings.
32. In a lasting machine, the combination with means for pulling an upper over a last successively in different locations along the side of the last as the shoe is presented by the operator in different positions, a shoe bottom rest and a side gage for controlling the shoe, and upper-fastening mechanism constructed to drive fastenings and movable inwardly over the bottom of the shoe to lay the marginal portion of the upper over a sole on the last prior to the driving of the fastening through the upper and into the sole, of an overlaying device mounted for movement into position for use to lay the marginal portion of the upper inwardly over the sole while moving with said upper-fastening mechanism in lasting the shoe with cement instead of with driven fastenings, a member for moving said device into and out of position for use on the shoe, and connections between said last-named member and the side gage for altering the position of the side gage both widthwise and heightwise of the shoe in setting said device for lasting the shoe with cement or with driven fastenings.
33. In a lasting machine, the combination with means for lasting a shoe successively in different locations along the edge of the shoe bottom as the shoe is presented by the operator in different positions, of a shoe bottom rest and a side gage for controlling the shoe, said side gage being adjustable widthwise of the shoe into different positions to determine the position of the shoe laterally in operating upon different portions of the shoe, and

means for imparting to the side gage in response to its movement widthwise of the shoe a movement of predetermined extent heightwise of the shoe.

34. In a lasting machine, the combination with means for lasting a shoe successively in different locations along the edge of the shoe bottom as the shoe is presented by the operator in different positions, of a shoe bottom rest and a side gage for controlling the shoe, means under the control of the operator for moving the side gage toward or from the bottom rest in directions widthwise of the shoe to vary the position of the shoe laterally, and means automatically operative in response to such movement for varying the position of the gage heightwise of the shoe.

35. In a lasting machine, the combination with means for lasting a shoe successively in different locations along the edge of the shoe bottom as the shoe is presented by the operator in different positions, of a shoe bottom rest and a side gage for controlling the shoe, a slide movable to adjust the side gage widthwise of the shoe into different positions to vary the position of the shoe laterally, and means for moving the gage relatively to the slide in response to such movement to vary the position of the gage heightwise of the shoe.

36. In a lasting machine, the combination with means for lasting a shoe successively in different locations along the edge of the shoe bottom as the shoe is presented by the operator in different positions, of a shoe bottom rest and a side gage for controlling the shoe, a slide for moving the side gage widthwise of the shoe toward or from said bottom rest to vary the position of the shoe laterally, spring means for holding the slide in its rearward position, and means under the control of the operator for moving the slide forwardly, said means being constructed and arranged to lock the slide in its forward position against rearward movement in response to pressure of the shoe against the gage.

37. In a lasting machine, the combination with means for lasting a shoe successively in different locations along the edge of the shoe bottom as the shoe is presented by the operator in different positions, of a shoe bottom rest, a slide, a side gage pivotally connected to said slide and arranged to cooperate with said bottom rest to control the shoe, means under the control of the operator for moving the slide toward or from the bottom rest to position the gage differently widthwise of the shoe in operating upon different portions of the shoe, and means operative in response to such movement for swinging the gage relatively to the slide to vary the position of its shoe-engaging end heightwise of the shoe.

38. In a lasting machine, the combination with means for lasting a shoe successively in different locations along the edge of the shoe bottom as the shoe is presented by the operator in different positions, of a shoe bottom rest and a side gage for controlling the shoe, said side gage being movable toward or from the bottom rest along an inclined path into different positions in operating upon different portions of the shoe, and means arranged to impart to said gage movement into one or the other of said positions at the will of the operator.

39. In a lasting machine, the combination with means for lasting a shoe successively in different locations along the edge of the shoe bottom as the shoe is presented by the operator in different positions, of a shoe bottom rest and a side gage for controlling the shoe, said side gage

being movable toward or from said bottom rest in directions widthwise of the shoe into different positions to determine the position of the shoe laterally, a stop for limiting movement of said 5 gage away from said bottom rest, spring means for moving said gage into the position determined by said stop, a hand lever, and connections between said hand lever and the gage for moving the gage against the resistance of said spring 10 means toward the rest into a different position in response to movement of the hand lever in one direction and for releasing the gage to the action of said spring means in response to movement of the hand lever in the opposite direction.

15 40. In a lasting machine, the combination with means for lasting a shoe successively in different locations along the edge of the shoe bottom as the shoe is presented by the operator in different positions, of a bottom rest and a side gage for 20 controlling the shoe, said side gage being movable toward or from said bottom rest in directions widthwise of the shoe into different positions, an adjustable stop for limiting movement of the side gage in one direction, spring means for 25 holding the gage in the position determined by said stop, a hand lever arranged to be swung by the operator, and connections between said hand lever and the gage for moving the gage against the resistance of said spring means into 30 a different position, said connections being constructed to lock the gage in said position against displacement in response to pressure of the shoe against it.

41. In a machine for lasting shoes in which the marginal portion of the upper is secured in lasted relation to a sole by an adhesive, an overlaying device for laying the marginal portion of an upper inwardly over the outer face of a sole on a last, a support for said overlaying device movable to carry the device inwardly over the sole, and mechanism mounted on said support for operating said overlaying device by impact substantially at the end of its inward movement to 10 cause it to force the overlaid margin of the upper more firmly into adhering relation to the sole. 5

42. In a machine for lasting shoes in which the marginal portion of the upper is secured in lasted relation to a sole by an adhesive, an overlaying 15 device for laying the marginal portion of an upper inwardly over the outer face of a sole on a last, a support for said overlaying device movable to carry the device inwardly over the sole, and mechanism on said support for operating said 20 overlaying device by impact to cause it to force the overlaid margin of the upper more firmly into adhering relation to the sole said mechanism comprising a spring-operated hammer for delivering a blow to said overlaying device, and 25 a latch for preventing movement of the hammer relatively to the overlaying device and for releasing it to the action of its operating spring substantially at the end of the inward movement of the overlaying device. 30
